UNITED STATES PATENT OFFICE.

RICHARD W. PARKER, OF NEWARK, NEW JERSEY.

CAP FOR PEN-HOLDERS.

SPECIFICATION forming part of Letters Patent No. 316,815, dated April 28, 1885.

Application filed July 11, 1884. (No model.)

To all whom it may concern:

Be it known that I, RICHARD W. PARKER, a citizen of the United States, residing in the city of Newark, in the county of Essex and State of New Jersey, have invented a new and useful Improvement in Caps for Pen-Holders, of which the following, taken in connection with the accompanying drawings, is a full, clear, and accurate description.

- 10 My invention is especially adapted for use in connection with fountain-pens; and it consists in providing the pen holder or case with a cap of such form that one portion of the cap can fit over or upon the part of the case or holder holding the pen, while the other part is adapted to fit over or upon or within the other end of the holder when the pen is in use. This construction of a pen-holder provides the pen, essentially, with a double cap, and thus 15 prevents the part of the cap coming in contact with the pen, which in pens of the ordinary construction is liable to become inky through leakage, and when placed upon the other end of the holder ink that end, and so soil the hand or dress of the user. By my improvement this 20 disadvantage is entirely done away with.

In the drawings, Figure 1 represents a pen-holder with my improved cap covering the pen, the cap being shown in section. Fig. 2 25 represents a sectional view of my improved cap. Fig. 3 represents the form where the cap fits within the holder.

My improvement is made as follows: A rep-

resents a fountain-pen holder with pen. *a* is the end of the holder, adapted to receive the 35 cap when the pen is in use.

B represents my improved cap, and is provided with the chamber *C* and the chamber or projecting part *D*. The chamber *C* is made sufficiently large to contain the pen and to fit 40 upon the portion of the holder holding the pen. The chamber or projection *D* is made of such size as to fit upon and contain or fit within the part *a*.

When it is desired to close the holder when 45 the pen is not in use, the chamber is placed over the pen, and thus effectually protects it.

When it is desired to use the pen, the cap *B* is removed from the pen and the chamber or projection *D* is placed upon the end *a* of the 50 holder. Any ink which may have leaked into the chamber *C* is thus held in that chamber without possibility of soiling the holder.

Having thus described my invention, what I claim, and desire to secure by Letters Patent, 55 is—

A cap for pen-holders, of which one end fits over the pen, and the other end is adapted to fit over or within the other end of the pen-holder, substantially as described.

In witness whereof I have hereunto set my hand this 7th day of July, 1884.

RICHARD W. PARKER.

In presence of—

ELWOOD S. LEARY,
WILLIAM EARL.
